(57) **CLAIM**

The ornamental design for a cruet assembly for holding various food substances, as shown and described.

DESCRIPTION

FIG. 1 is a top and side perspective view of a cruet assembly for holding various food substances, showing my new design;

FIG. 2 is a bottom and side perspective view thereof;
FIG. 3 is a side elevational view thereof;

FIG. 4 is a side elevational view thereof rotated about a vertical axis from the position shown in FIG. 3;

FIG. 5 is a top plan view thereof;

FIG. 6 is a bottom plan view thereof; and,

FIG. 7 is an exploded side elevational view thereof.
